FLOWMETER CONDUIT

Arne Wibring, Jonkoping, Sweden, assignor to
Aktiebolaget Svenska Flaktfabriken

Filed Feb. 8, 1974, Ser. No. 440,800

Claims priority, application West Germany Aug. 21, 1973

Term of patent 14 years

Int. Cl. D10—04

U.S. Cl. D10—96

FIG. 1.

FIG. 2.

FIG. 1 is a side and end perspective view of a flowmeter conduit showing my new design, the opposite sides not shown being substantially identical but without the cylindrical tubing outlet housing; and

FIG. 2 is a right end elevational view thereof, the left end being a mirror image thereto.

I claim:

The ornamental design for a flowmeter conduit, as shown and described.
